1

The present invention relates to electron lens systems such as are employed in cathode ray tubes, electron discharge valves and other electron discharge devices for focusing or forming flattened or ribbon-shaped electron beams.

In electron lens systems of the kind referred to, the action of the lens is required to be similar to that of a cylindrical lens. That is to say, in the ideal case of an electron lens having straight focal lines, the form of a plane cross-section of the lens field at right angles to the focal line will be invariant as the plane of the cross-section is translated or moved in a direction parallel to the focal lines, the lens field thus being said to have translational symmetry in a direction parallel to the focal lines.

To produce an electron lens which is approximately translationally symmetrical, electrode systems may be employed in which the lens field is produced by charging pairs of parallel plane electrodes disposed with the electrodes of one pair parallel to the electrodes of another and mounted so that the electrode pairs have mirror symmetry about a common plane. Alternatively pairs of slotted diaphragms may be employed.

One object of the present invention is to provide an electrode system for forming an electron lens field which acts like a field of translational symmetry, and wherein the dimensions of the electrode system focusing an electron beam having a cross-section of a given width can be made less than in the case where the lens-forming electrode system is made up of plane electrodes.

Another object of the invention is to provide an improved method of and means for providing cylindrical focusing action substantially over the entire width of an electron lens.

A further object of the present invention is to provide an electrode system for forming an electron lens which is to some extent translationally symmetrical and in which the focal length of the lens is substantially constant at least over the path of the beam to be focused, and wherein the lens-forming electrodes are so formed as to provide shielding for an electron beam passing through the lens.

According to the present invention there is provided an electron discharge device arranged to have a beam of electrons projected within it and having an electrode system arranged about the path of said beam for forming an electron lens, said electrode system comprising lens-forming electrodes having curved surfaces or edges facing each other with said path between them the curvature of said surfaces or edges being such

2

that electrons passing through the lens field can be formed more nearly as desired than would be the case if said transforming electrodes had parallel plane or straight surfaces or edges facing each other.

In the case where said lens-forming electrodes are in the form of slotted diaphragms, the slots in said diaphragms being tapered towards their edges or being rectangular in form, said slots may be limited by having metal strips applied slantwise across the corners of the slots.

In a preferred form of the invention said lens-forming electrodes may have curved surfaces facing each other which wholly or partly embrace the path of said beam and afford electrical shielding therefor in respect of field penetration edge-wise of the lens-forming electrodes.

The invention further includes an electric circuit arrangement including an electron discharge device having a cathode and means for deriving a beam of electrons from said cathode, and electrodes disposed about the path of said beam, said electrodes having curved surfaces or edges facing each other about the path of said beam, and means for applying potentials to said electrodes for focusing said beam, the curvature of said surfaces or edges being such that said beam can be focused more nearly as desired than would be the case if said electrodes had parallel plane or straight surfaces or edges facing each other.

In order that the said invention may be clearly understood and readily carried into effect, the same will now be more fully described, reference being made to Figures 1 to 3 of the accompanying drawing illustrating schematically a typical prior art device, and further reference being made by way of example to Figures 4, 5, 6 and 7 of the accompanying drawing, of which Figure 4 shows an end view corresponding to Figure 3 of a pair of lens-forming electrodes made in accordance with the invention.

Figure 5 is a diagrammatic view in sectional side elevation showing an electrode system which may be treated in accordance with the invention.

Figure 6 is a front elevational view of one of the electrodes of Figure 5 treated in accordance with the invention, and

Figure 7 is a graph showing a characteristic curve of the arrangement of Figure 5.

Figure 1 of the accompanying drawing is a diagrammatic sectional view through a simple electrode system for providing an electron lens having translational symmetry for focusing a ribbon-shaped electron beam. In this case, the electrode system is constituted by two pairs of plane

electrodes 1, 2, and 3, 4, respectively, each pair of electrodes having the same length and separation. The aforesaid plane of mirror symmetry is represented by the line OZ and rays of electrons 5 and 5' are shown as projected into the lens field parallel to OZ and caused to cross OZ at the point F which represents the location of one of the focal lines of the lens. The lens field is produced between the two pairs of plates by charging the two pairs each to a different potential, the electrodes 1 and 2 being charged in the case illustrated to a potential V_1 which is lower than the potential V_2 to which the electrodes 3, 4 are charged. A lens, formed in the manner described with reference to Figure 1, resembles in its action a lens produced by charging two coaxial cylindrical tubes as described, for example, in chapter 2 of the Cambridge Physical Tract "Electron Optics," published by the Cambridge University press in 1939. That is to say, the lens field produced in the manner described above has a midplane shown at M in Figure 1 perpendicular to the plane of mirror symmetry of the electrodes represented by OZ between the electrode pairs and has six cardinal "points," including two focal points, two principal points and two nodal points, as in the case of a cylindrical optical lens, both the principal points being located to the left of the midplane M, for example, at P and P₁ as shown in the drawing. Both the focal lengths of the lens formed by the four plates are somewhat shorter than those of the lens formed by two tubes having diameters equal to the separation of the plates and charged to the same potentials as the plates, but the aperture error or spherical aberrations produced in each case are similar in magnitude. It will be appreciated that for good focusing the angles of divergence of the electron beam to be focused must be confined within reasonable small limits such that the angle at which any ray such as 5 or 5', derived from an electron source E, makes with the plane represented by OZ is so small that third order effects can be neglected.

Ideally, the parallel plane electrode employed in forming a cylindrical electron lens should be of infinite extent in directions of the focal lines of the lens. This is, of course, impossible in practical arrangements, but, nevertheless, the width of plates is required to be much greater than that of the beam to be focused. Consequently, in a lens employing parallel plane focusing electrodes the housing of the electron discharge device in which the electrodes are enclosed must have a greater cross-section than that necessary to accommodate the path of the beam, the unused cross-sectional area in this case being much greater than in the case of a field formed by charging cylindrical electrodes.

Furthermore, the electrode structure employed should afford shielding for the path of the beam. Cylindrical lens-forming electrodes provide perfect shielding, except possibly at a gap between the electrodes which can readily be covered by an outer annulus, but with plane lens-forming electrodes as above described, shielding means must be provided at the edges of the lens-forming electrodes. Usually, the shielding means are combined with the lens-forming electrodes and each pair of plane electrodes is replaced by an open-ended box-shaped electrode in the manner illustrated in Figures 2 and 3 of the accompanying drawing, which illustrate respectively a perspective view and an end view of an electrode system for producing an electron lens, and in which the

lens-forming electrodes are combined with shielding means as above referred to.

Referring to Figure 2, it will be seen that one lens-forming electrode comprises upper and lower sides 1 and 2 respectively corresponding to the electrodes 1 and 2 of Figure 1 and sides 6 and 7 which provide shielding for the path of the beam while the second lens-forming electrode comprises upper and lower sides 3 and 4 corresponding to the electrodes 3 and 4 of Figure 4 and sides 8 and 9 for providing the shielding.

The lens system illustrated in Figures 2 and 3 will be discussed analytically with reference to the system of co-ordinate axes x, y, and z represented to the left of Figure 2, in which the x-axis is parallel to the line of intersection of the mid-plane and the plane of mirror symmetry of the electrode system represented by OZ in Figure 1; the y-axis is perpendicular to the x-axis and to the plane sides 1, 2, 3 and 4 of the lens and the z-axis is perpendicular to the mid-plane and lies in the aforesaid plane of mirror symmetry. The aperture of the lens is given by the dimensions $2x_B$ and $2y_B$ as shown in Figure 3. In an arrangement such as that shown in Figures 2 and 3, the shielding sides 6, 7, 8 and 9 are found to have a distorting effect on the field of the lens, such that the lens field ceases to be translationally symmetrical. This distorting effect becomes appreciable when focused electrons approach the side shields 6, 7, 8 or 9, within a distance of the order of the aperture dimensions $2y_B$. Thus, from this point of view it is advantageous to make the distance between the plates 1, 2, and 3, 4, as small as possible so as to keep the value of y_B small. However, in practice the minimum value to which the separation between the sides 1, 2 and 3, 4, can be reduced is limited due to the fact that if the sides are too close together the lens becomes unsatisfactory in respect to its focusing properties for rays which approach too close to the plates 1, 2, 3, 4. Thus, if y_e represents the thickness of the beam to be focused, then the ratio y_e/y_B must have a value less than a certain fixed small value if satisfactory focusing of the beam is to be obtained. Thus, the value of y_B must be made great in comparison with the thickness of the beam, and the shields 6, 7 and 8, 9 must be separated to a greater extent than is necessary merely to accommodate the beam. This is especially troublesome where the beam is not many times wider than it is thick as the proportion of waste space to used space is greater the narrower the beam.

The electron optical effect of the side shields 6, 7 and 8, 9 is found experimentally to be capable of being resolved into two components which account for practically the whole of the distortion produced. The first component arises from the fact that the four side shields 6, 7, 8, 9 serve as lens-producing electrodes in the same way as the sides 1, 2 and 3, 4, and thus produce a focusing of the electron beam about the y-axis in addition to the focusing about the x-axis which is produced due to the action of the sides 1, 2, 3, 4. This effect is not, in general, very important, because the focal length of the lens system constituted by the side shields is great in comparison with the focal length of the lens produced by the electrodes 1, 2, 3, 4. For example, if x_B is greater than $2y_B$ the focal length of the lens formed by the side shields is more than ten times as long as the one produced by the sides 1, 2 and 3, 4. The second component arises from the fact that the presence of the side shields produces a

variation in the focal length of the lens field produced by the electrodes 1, 2 and 3, 4 in a direction parallel to the x -axis. That is to say, the effect of the side shields is to cause a flat ribbon-shaped beam to be focused on a curved line through F instead of a straight line, so that the beam cannot be focused on a plane screen.

Referring to Figure 4a of the drawing, the curved lens-forming electrodes employed in accordance with the invention are indicated at 11 and 12. These electrodes correspond to the box-shaped electrode including the sides 1, 2, 6 and 7, shown in Figures 2 and 3 and are continued until they meet each other at their edges 16 and 17 so as to provide complete shielding for a beam passing between them. In order to form a lens field corresponding to that produced by the arrangement of Figure 2, a further pair of lens-forming electrodes as shown in Figure 4b, would be provided, arranged immediately behind the electrode shown in Figure 4a.

It will be readily appreciated that the effect of employing lens-forming electrodes curved in the manner indicated in Figure 4 such that pairs of lens-forming electrodes are more widely spaced in the center of the lens field than at the edges thereof will be to produce a lens of which the focal length will be shorter towards the edges of the lens field than would be the case if pairs of flat lens-forming electrodes such as those represented in Figure 1 were employed. Thus, it will be seen that by appropriately choosing the curvature of the electrodes 11 and 12 the focal length of the lens obtained can be made to vary in a desired manner in a direction parallel to the x -axis.

In order to make the invention clear, the method of shaping the lens-forming electrodes in the case where it is desired to make the focal length of the electron lens constant in a direction parallel to the x -axis will be described by way of example. In this example the lens constructed had an aperture such that $x_B = 2y_B$ and a ratio V_2/V_1 of four. In making the lens, a lens formed of box-shaped electrodes having the same overall dimensions and of which the cross-section is indicated in dotted lines at 19 in Figure 4 was investigated by tracing the paths of rays projected in planes at right angles to the x -axis and intersecting that axis at x_0, x_1, x_2, x_3 respectively, x_0 being on the axis of the lens-forming electrodes, x_1 being equal to $\frac{1}{2}y_B$, x_2 being equal to y_B and x_3 equal to $\frac{3}{2}y_B$. In this case the following results were obtained giving the position of the cardinal points F and P with respect to the mid-plane M (see Figure 1) of the lens system, taking y_B as unity. At the positions x_0 and x_1 it was found that effectively the distance MF was 3.0, MP 2.4 and the focal length f, that is the distance between PF was 5.4; whilst at x_2 MF was 4.0, MP 3.8, and f 7.8; and at x_3 MF was 7.1, MP 3.1, and f 10.2. By comparing the results obtained at positions x_0 and x_3 it can be seen that the distance MF for the two box lens is increased by a factor

$$\frac{7.1}{3} = 2.4$$

at the position x_3 near the edge of the lens field over its value at the middle of the lens-forming electrode system.

Now to provide a lens corrected in such a manner that the mid-focal length of the lens is constant throughout the width of the lens the aperture has to be shaped so that at any position

x along the x -axis where the aperture dimension is y , the value of y is such that

$$\frac{y}{y_B} = \frac{MF_0}{MF_x}$$

where MF_0 is the value of the mid-focal length at the center of the lens formed of box-shaped electrodes having the same values of x_B and y_B as the corrected lens, and f_y is the focal length of the lens formed of box-shaped electrodes at the position x along the x -axis. Thus, to produce a corrected lens the electrodes 11 and 12 of Figure 4 must be so curved that at the position x the aperture $y_1 = y_B$; at the position x_2 the aperture y_2 is $\frac{3}{4}y_B$; and at the position x_3 the aperture y_3 is

$$\frac{3}{7.1y_B}$$

Thus, the required form of the electrodes 11, 12 is determined. In general it is found that the forms of electrodes 11 and 12 required to give straight line focusing will be substantially the same for voltage ratios V_2/V_1 between 2 and 6. If the voltage ratio is very different from four, however, the ratio of the distance MF at a position away from the middle of the lens to the distance MF at x_0 is expected to be different from the ratio derived from the results given above and the curvature of the electrodes 11 and 12 will consequently be different. Moreover, if the electron lens is required to focus a converging or diverging beam instead of a parallel beam, then the form of the electrodes 11 and 12 must be varied in accordance with the convergency or divergency of the beam, the distance between the mid-plane M and the image being taken as the basis of calculation instead of as the distance between mid-plane M and the focal point F. It is also possible that the focusing of the box lens may be further improved if the spacing of the plate elements 11 and 12 near their edges 16 and 17 is varied from that obtained in the manner described above, as in the region of the edges the mid-focal length obtained is not longer substantially proportional to the spacing between the plates.

It will be appreciated that if it is required to focus a rectangular beam on a curved line rather than a straight line the mid-focal distance of the lens will be required to vary across the lens and the shape of the plate element in a system according to the invention can be adjusted as desired to give the required form of the focal line.

In some cases instead of making the electrodes 11 and 12 meet each other as illustrated in Figure 4, they may be terminated before they meet and the shielding of the beam path through the lens may be completed by providing side plates such as 5, 6, 7 and 8, in Figures 2 and 3. However, the lens will not be thoroughly corrected in this case.

This invention is also applicable to electron lenses in which the lens-forming electrodes are in the form of slotted diaphragms. In such an arrangement where the diaphragms are provided with simple rectangular slots, it is found that the lens field is such as to cause undesired curvature of the focal line of the lens similar to that which occurs when box-shaped elements are employed as in the arrangement of Figures 2 and 3. This curvature may be eliminated by forming the slots in the diaphragms so that the facing edges of the slots are curved in the same manner as the plates 11 and 12 of Figure 4.

A simple diaphragm lens is represented in Figure 5, the diaphragm elements being indicated therein at 20 and 21, these elements being mounted on the ends of box-shaped or tubular electrodes 22 and 23 respectively, which shield the path of the beam to or from the elements 20 and 21. A front view of the element 20 is shown in Figure 6, wherein the rectangular slot in the element is shown at 24. In order to produce an electron lens, a suitable potential difference is established between the electrodes 20 and 21. The arrangement of Figure 5 will be discussed analytically with respect to co-ordinate axes x , y and z disposed in the same way as the correspondingly referenced axes in Figures 2 to 4 of the drawing.

A lens consisting in a system formed in the manner described with reference to Figure 5 will focus a flat beam at a line in an xz plane, which is straight in the vicinity of the central yz plane, but becomes increasingly curved outside this region, thus, for example, in the case of a lens in which the diaphragms 20 and 21 have semi-apertures x_B 10 mm. and y_B 3 mm. and are spaced from each other by a gap of 1 mm., if the ratio V/V_1 between the potentials applied to electrodes 20 and 21 respectively is 1.7, then a beam passing first through electrode 20 and then through electrode 21 will be focused at a line which is straight to distances equal to 0.4 x_B on either side of the z -axis, but then begins to become curved so that while at the center of the field the mid-focal length is 29 y_B at $x = \pm 0.8 x_B$ the focal length is 59 y_B . In applying the invention to the correction of such a lens it is sufficient for most purposes to limit the apertures in the diaphragms 20 and 21 by means of inclined metal strips 25 (see Figure 6) these inclined strips being applied across the corners of the apertures. The strips 25 may be welded on the diaphragms 20 and 21 and are arranged so as to stop out the triangular portions 26 at the corners of the slot having horizontal and vertical sides 0.5 x_B and 0.31 y_B respectively. With a lens so corrected the focal line is straight up to distances equal to 0.8 x_B from the z -axis.

In any given case the best position of strips such as 25 (Figure 6) should be found experimentally. For this purpose it is first necessary to ascertain the degree of correction necessary at two or more regions away from the middle parts of the slots. For example, in Figure 7 the semi-aperture y_1 of the slot at the point $x=0.8 y_B$ is plotted against the measured mid-focal length MF. The semi-aperture y_1 is measured in terms of the semi-aperture y_B . Typical results obtained for the mid-focal lengths are indicated by the dots 31 to 34 in Figure 7 of which the dot 31 shows the mid-focal length in the plane $x=0.8 x_B$ when there is no restriction of the slot width by strips 25, (i. e., $y_1 = y_B$), whilst the points 32, 33 and 34 show results obtained for the mid-focal length as the slot width is progressively restricted. The dotted line 35 in Figure 7 indicates the value of the mid-focal length in the central yz plane of the lens. The curve A intersects the line 35 at a point 36 corresponding to a semi-aperture of 0.7 y_B . Thus the strips 25 should be applied in such a manner as to reduce the semi-aperture of the slot in the plane $x=0.8 x_B$ to 0.7 y_B . If the reduction of the semi-aperture required to be effected by the strips 25 is determined for another value of x along the slot, then each strip can be positioned to give the two reductions found to be necessary at

the two points in respect of which an investigation has been made, and it will be found that the strips disposed in this way give a high degree of correction in the lens. It is, then possible, once the correct form of the slot has been investigated, to punch the slot to this size out of a diaphragm and thus dispense with the strips 25. Only punched slots, of course, will be used in mass production. It will be observed that the correct width of slot found by the empirical method described above differs from the width of slot given by the rule employed in obtaining the curvature of the elements 11 and 12 of Figure 4, the reason for this difference being that in the immediate neighborhood of the edges of the slot the mid-focal length obtained is far from proportionality with the slot width.

For any particular size of slots in the diaphragms 20 and 21 of Figure 5 the curvature of the focal line obtained will depend on the ratio of the voltages applied to the electrodes 20 and 21, and the form of the slot required to produce a given degree of correction will depend on this ratio.

Having now particularly described and ascertained the nature of my said invention, and in what manner the same is to be performed, I declare that what I claim is:

1. In electron apparatus including means for generating an electron beam, an electron lens structure disposed in the path of said beam comprising at least two cooperative tubular electrodes each defining lens apertures for said beam, said aperture defining electrodes having intersecting concave surfaces symmetrically disposed about and facing the transverse axis of said lens to provide cylindrical focusing action substantially over the entire width of said lens.

2. In electron apparatus including means for generating an electron beam, an electron lens structure disposed in the path of said beam comprising at least two cooperative tubular electrodes each defining lens apertures for said beam, said aperture defining electrodes being shaped to include oppositely disposed curved edges having chords symmetrical with respect to the transverse axis of said electron beam to provide cylindrical focusing action substantially over the entire width of said lens.

3. In electron apparatus including means for generating an electron beam, an electron lens structure disposed in the path of said beam comprising at least two cooperative tubular electrodes each defining lens apertures for said beam, said aperture defining electrodes being shaped to include oppositely disposed curved surfaces having chords symmetrical with respect to the transverse axis of said electron beam to provide cylindrical focusing action substantially over the entire width of said lens.

4. In electron apparatus including means for generating an electron beam, an electron lens structure disposed in the path of said beam comprising at least two cooperative tubular electrodes each defining lens apertures for said beam, said aperture defining electrodes being shaped to include oppositely disposed intersecting curved surfaces having chords symmetrical with respect to the transverse axis of said electron beam to provide cylindrical focusing action substantially over the entire width of said lens.

5. In electron apparatus including means for generating an electron beam, an electron lens structure disposed in the path of said beam comprising at least two cooperative tubular electrodes

each defining lens apertures for said beam, said aperture defining electrodes being shaped to provide rectangular apertures symmetrical with respect to the transverse axis of said electron beam and having predetermined corner portions thereof masked out symmetrically with respect to said transverse axis to provide cylindrical focusing action substantially over the entire width of said lens.

6. Apparatus of the type described in claim 1 including means for applying potentials to each of said electrodes for focusing said electron beam.

7. Apparatus of the type described in claim 3 including means for applying potentials to each of said electrodes for focusing said electron beam.

8. In electron apparatus including means for generating an electron beam, an electron lens structure disposed in the path of said beam comprising cooperative concave electrodes symmetrical with respect to the transverse axis of said electron beam, said electrodes having intersecting arcuate surfaces having common chords on said transverse axis of said lens to provide cylindrical focusing action substantially over the entire width of said lens.

9. Apparatus of the type described in claim 8 including means for shielding said electron beam intermediate predetermined adjacent edges of said electrodes.

10. An electron-discharge device arranged to have a beam of electrons projected within it and having an electrode system arranged about the path of said beam for forming an electron lens, said electrode system comprising lens-forming electrodes having intersecting arcuate edges facing each other symmetrically disposed about said path, the curvature of said edges being such that electrons passing through the lens field can be focused more nearly as desired than would be

the case if said lens-forming electrodes had parallel plane edges facing each other.

5 11. In electron apparatus including means for generating an electron beam, an electron lens structure disposed in the path of said beam comprising at least two cooperative tubular electrodes each defining lens apertures for said beam, the cross-sections of said aperture defining electrodes being in the form of concave elements symmetrically disposed about and facing the transverse axis of said lens to provide cylindrical focusing action substantially over the entire width of said lens.
